SHALE RETORTING PROCESS

Clyde H. O. Berg and John E. Hines, Jr., Long Beach, James R. Hunt, Fullerton, Cloyd P. Reeg, Long Beach, and John H. Ballard, Whittier, Calif., assignors to Union Oil Company of California, Los Angeles, Calif., a corporation of California

Application April 8, 1957, Serial No. 651,501

23 Claims. (Cl. 202—95)

This invention relates in general to improvements in solids-fluid contacting and particularly to an improved apparatus for the production of hydrocarbon gases and oils from solids by thermal means. Applicable solids include such oil-producing and oil-containing materials as oil shale, tar and oil sands, oil-saturated diatomite, bituminous and sub-bituminous coals, and the like. The description will be conducted in terms of the eduction of shale oil and gas from oil shale for the sake of simplicity and with the understanding that the process and apparatus are applicable in general to other solids from which oils and gases can be produced by solids-fluid contact, and to solids-fluid contacting processes in general.

Some processes for the eduction of shale oils and gases involve the downward passage of shale rock as a moving bed by gravity through a vertical heat treating kiln. During this passage the solids are heated to eduction temperatures by direct or indirect means. From a thermal efficiency standpoint the direct heating means in which a countercurrent contact of hot gases with the shale rock is employed is preferred. To avoid the large fuel consumption otherwise required, most of these processes involve the direct injection of air or other oxygen-containing gas into the bottom of the kiln to burn the carbonaceous residue from the spent shale. This generates hot flue gases needed to heat the rock. However, some difficulties are encountered with the fusion of the spent shale due to this burning, and frequently the fused or partially fused rock plugs the air inlet requiring a shutdown. Since all of the hydrocarbon product is removed at the top of the kiln, it must be removed as a vapor or mist so that the process requires extensive cooling and condensing facilities and usually results in thermal decomposition of a considerable part of the hydrocarbon.

Other shale eduction processes have successfully avoided the large fuel and condensing water requirements by utilizing an upflow of shale rock and a downflow of heating gas. The shale is fed upwardly successively through a perforated product fluid-shale rock disengaging section and a heat treating and kiln section. Air or other oxygen-containing gas enters the top of the heat treating section, is preheated in cooling the hot shale ash, burns the carbonaceous residue from the spent shale forming hot flue gas and the hot ash, and the hot flue gases continue downwardly to heat the shale rock to eduction temperatures. The hydrocarbon oils and gases are thus evolved in the eduction zone forming spent carbonaceous shale and a mixed fluid phase containing flue gas and oil vapors and liquids. The whole vapor phase passes downwardly in direct contact with the cool raw shale, and is cooled thereby condensing the hydrocarbon oil and preheating the raw shale. The liquid and gaseous products are drawn off at the perforated disengaging section and are thus separated from the upwardly moving shale rock. A solids feeder passes the shale rock upwardly through the disengaging and heat treating sections and displaces the shale ash out the top of the unit. The process supplies its own fuel in the form of carbonaceous spent shale. It cools

2

and partially condenses its own product in preheating the cool raw shale rock.

One principal problem of these processes involves the presence of solids fines in the solids to be thermally treated and in the present illustration these fines are exemplified by shale fines in the feed. In the downflow solids processes, a screening step is required to separate from the rock fed to the process the shale fines whose average dimensions are less than about 0.25 inch. In the upflow shale process, the problem is aggravated with screw feeders, and non-vertically acting piston feeders. With such solids feeders it has been found that the quantity of fines in the feed increases as much as 100% or more when such solids feeders are employed and that up to about 50% of the feed is reduced to fines in the feeder.

In the present invention a vertically acting reciprocating piston feeder, hereinafter more fully described, is used. This piston feeder successfully passes shale rock upwardly through the apparatus of this invention without the formation of substantial quantities of additional fines. The process and apparatus are also capable of a substantially complete retorting of valuable products from those fines which naturally occur in the unscreened feed and thus they accomplish what all the previous retorting processes were incapable of accomplishing.

In the upflow shale process, the fusion problem is encountered particularly with shales which produce more than about 30 gallons per ton of oil, or where the carbon content of the spent shale is unusually high so as to generate an excess of heat during the carbon burn-off step. These slagging conditions are not nearly so serious as in the downflow process in which the entire weight of the solids bed rests on the fused materials causing it to agglomerate. However, slagging conditions are sometimes encountered between about 2000° F. and about 3000° F., depending upon the mineral constitution of the material.

In the present invention these difficulties have been substantially eliminated, even in the apparatus applied to commercial scale solids processing, by the invention shown in the accompanying drawings and described subsequently. Particularly this involves the agitation of the burning residue in the upwardly rising solids mass. The agitation is accomplished by means of a plurality of plows extending downwardly into the solids bed. The plows rotate about the central vertical axis of the kiln. The effect of this agitation is to prevent slagging conditions in the burning zone from inhibiting free and uniform gas flow downwardly through the mass of solids being treated. The plows are adapted also to be self-cooling and in this way a portion of the heat liberated in the burning zone is removed from the system. The burning zone is maintained with its approximately intermediate point or horizontal plane intersecting the lower extremities of the plows. Rotation of the plows through the solids bed prevents the slagging problems referred to above.

The present invention is therefore directed to an improved upflow shale retorting apparatus, as illustrative of these solids heat treating processes in which the solids pass upwardly countercurrent to a downflow of heat treating fluid, and in which the burning of residual carbon on the spent solids is effected in the presence of a substantially continuous agitation in the burning zone of the rising solids by means of the improved apparatus herein disclosed.

It is a primary object of the present invention to provide an improved solids-fluid treating apparatus.

A specific object of this invention is to provide an improved autothermic or self-heating apparatus for the production of oil and gas from oil-producing or containing solids such as oil shale, tar or oil sands, and the like.

It is a particular object of this invention to provide

in such apparatus an improved system for agitating the solids during combustion of the residual carbon thereon.

A more particular object is to provide, in the upflow solids retorting apparatus, an improved mechanism capable of continuously agitating the burning solids located 3 to 6 feet and deeper in the rising solids bed, where the bed contains solids of up to about 12 inches in nominal mesh size, and where they are burned at temperatures between 2000° F. and 3000° F.

A still further object of this invention is to provide a self-cooling heavy-duty solids agitating or plowing apparatus of particular structural design enabling it to accomplish successful solids agitation under the conditions referred to above and yet resist the thermal and mechanical load stresses generated by such high temperatures and deep plowing conditions.

Other objects and advantages of the present invention will become more apparent to those skilled in the art as the description and illustration thereof proceed.

The improved apparatus, and the particular elements thereof, of the present invention will be most clearly described to those skilled in the art by reference to the accompanying drawings in which:

Figure 1 is a vertical elevation view in partial cross section of the complete upflow solids-fluid contacting apparatus of this invention as applied to the retorting of oil shale and indicates at the upper end thereof the rotary equipment necessary to accomplish the deep and high temperature solids plowing referred to previously.

Figures 2 and 3 are elevation views in cross section taken at right angles to one another showing the plow coolant coolers through which the coolant is circulated by natural convection from the plows and is cooled against atmospheric air.

Figure 4 is a plan view of the apparatus shown in Figure 1, but in which the coolant coolers have been removed for sake of clarity, and showing the stationary ring girder, hydraulic drive cylinders, the ratchet ring, the plow drive ring, and the central plow support ring beneath which by dotted lines are indicated the general azimuthal disposition of the several plows.

Figure 5 is a perspective view of the under side of the plow support ring showing again the azimuthal disposition of the plows, their connection to the lower surface of the plow support ring, and the manner in which they extend downwardly in a helical curve and are terminated at their lower ends in an abrasion resistant plow shoe, and

Figures 6 through 12 are cross sectional views of the plows taken at the places indicated in Figure 5 and which show in detail the internal construction of the plows and shoes.

Referring now more particularly to Figure 1, the entire apparatus in which the particular improved solids agitation or plowing mechanism of the present invention is used, is shown in the form in which the apparatus is applied to the continuous retorting of oil shale to produce shale oil and gas. The apparatus consists essentially of a feeder case 10, a formaminate solids-fluid disengaging means 12, and heat treating or kiln means 14 superimposed one above the other in the manner shown. Superimposed at the top of kiln 14 is the entire rotating mechanism employed in the present invention for agitating continuously the burning solids.

Oil shale is introduced into hopper 16 and is fed by means of the solids feeder upwardly successively through disengaging zone 12 and retorting zone or kiln 14. The solids feeder comprises a solids feeder cylinder 18 disposed within feeder case 10 and supported from trunnion 20 permitting it to be oscillated in a vertical plane so that the upper opening of the cylinder is aligned alternately with the bottom of hopper 16 and the lower solids inlet to disengaging zone 12. The hydraulic feeder cylinder 22 provided with piston rod 24 and feeder piston 26, is disposed within solids feeder cylinder 18 and oscillates with it. Guards or shoes 28 and 30 curve away from

the sides of the upper opening of feeder cylinder 18 and serve to close the lower outlet of hopper 16 when feeder cylinder 18 is in the position shown, and also to close the lower solids entrance to disengaging section 12 when the feeder cylinder is oscillated to the left in registry with the shale hopper. The oscillatory motion of feeder cylinder 18 is provided by means of oscillating hydraulic cylinder 32 connected at pivot 34 to the inside of feeder case 10, and also connected at pivot 36 by means of piston rod 38 to the side of feeder cylinder 18.

The cyclic action of hydraulic cylinders 22 and 32, necessary to achieve the removal of fresh solids from hopper 16 and the introduction thereof upwardly from below into the vertical path through disengaging section 12 and heat treating section 14 consists of four repeated steps. First, the oscillating hydraulic cylinder 32 retracts with hydraulic feeder cylinder 22 in the position shown inclining solids feeder cylinder 18 to the left into alignment with shale hopper 16. Second, the hydraulic feeder cylinder 22 retracts moving piston 26 downwardly toward trunnion 20 drawing a charge of fresh shale and any recirculated fines into the top of feeder cylinder 18. At this time guard 30 seals the lower solids entrance to disengaging section 12. Third, the hydraulic oscillating cylinder 32 extends moving feeder piston 18 back into the vertical position shown, but in which piston 26 is at its lowest position, not shown. Fourth, the hydraulic feeder cylinder 22 extends forcing the charge of raw shale upwardly into the lower part of disengaging section 12. The entire mass of solids moves upwardly through sections 12 and 14 and some spent solids discharge at the top of heat treating section 14. At this time guard 28 is in the position shown closing the lower outlet of the shale hopper. These four steps are then repeated to maintain a substantially continuously upward flow of solids.

A pair of inclined sloping baffles 40 and 42 are provided along the bottom of feeder case 10 extending in the general direction of the plane of oscillation and closely beside trunnion 20 forming in feeder case 10 a V-shaped bottom. Along the lower line of intersection of this trough is extended screw conveyor 44, driven by rotary means not shown but conventional. This conveyor removes small traces of solids fines which sometimes leak past guards 28 and 30 and accumulate in the feeder case. To assist conveyor 44, a stream of product oil is introduced under pressure into feeder case 10 through line 46 and is removed in the form of a fines slurry from outlet 48 at the discharge end of the conveyor. This slurry is pumped by means of pump 50 at a rate controlled by valve 52 through line 54 either into the bottom of hopper 16 or into fines distributor 56.

As indicated previously the solids move successively in an upward direction as a dense, fluid-permeable, continuous mass through the perforated fluid disengaging section 12 and through heat treating section 14. The downward countercurrent flow of fluid is maintained by means of gas blower 60 which takes suction through line 62 at the upper end of product separator chamber 64 surrounding the perforated disengaging section 12. Air therefore enters the top of heat treating section 14, and the flow of fluid passes downwardly successively through ash cooling and air preheating zone 66, spent shale burning zone 68, retorting or eduction zone 70, raw shale preheating and product fluid cooling and condensing zone 72, and continues into fluid separator section 12. The fluid flows, still under the influence of blower 60, through perforations 74 into product separator 64. The condensed shale oil accumulates in the lower portion of product separator 64 providing a liquid level at the approximate position indicated at 76. The feeder case 10 is also filled with this product oil.

The product separator 64 is provided with a VV-shaped bottom comprising two pair of inclined baffles, one of which is indicated as 78 and the intersection lines

of which run generally parallel to the plane of drawing as normally viewed. The baffles are inclined with respect to one another at angles of about 45° and when viewed at 90° from the drawing present the VV-shaped cross section. Along the bottom of each V-shaped pair of baffles is extended a primary screw conveyor, one of which is indicated in Figure 1 at 80. It is provided with rotary drive means 82 and delivers settled solid shale fines, which fall through slots 74 and settle in the liquid product, into transverse secondary conveyor 84. The fines are here accumulated from both primary conveyors and discharged by means of conveyor 84 into fines distributor 56.

This distributor is centrally located at the bottom of shale hopper 16 so that the fines are concentrated in the interior of the charge of larger sized shale particles into which they are introduced. This prevents any subsequent fall-through of these same fines into product separator chamber 64 and insures that they be carried upwardly with the raw shale feed and treated therewith in heat treating section 14.

As indicated previously, the liquids and the gases separate from each other in separator chamber 64. The liquid phase, principally shale oil, flows from separator 64 through line 86 under the influence of product oil pump 88 at a rate controlled by valve 90 and liquid level controller 92. Part of the product flows as previously described through line 46 controlled by valve 94 to flush solids fines from feeder case 10.

Blower 69 previously described withdraws non-condensed gases from the upper portion of separator 64 and passes them through line 96 into mist separator 98 at a rate controlled by valve 100. Pressure controller 102 may control valve 100 in order to maintain a predetermined subatmospheric pressure in separator chamber 64, or it may, if desired, maintain a predetermined differential pressure between the top and the bottom of heat treating section 14.

In mist separator 98 residual traces of entrained liquids are separated from the gas stream and are passed through line 104 controlled by valve 106 into combination with the shale oil product produced through line 108. The non-condensed gases flow through line 110 provided with valve 112. Ordinarily these gases are discharged to the atmosphere and they comprise essentially carbon monoxide, nitrogen, and carbon dioxide with relatively small amounts of hydrocarbon gases sufficient to give the gas a heating value of about 90 B.t.u. per cubic foot. This gas may be used as fuel with special burners, or if desired, part or all of it may be reintroduced as recycle gas into the top of heat treating section 14 to dilute the incoming air in order to moderate combustion temperatures and the conditions of eduction.

Heat treating section 14 is conical in shape, as is disengaging section 12, but has a considerably smaller apex angle. It is provided on its outer surface with a plurality of vertically extending radial fins 114, the outer edges of which are enclosed in jacket 116 providing a series of vertical passageways. These are open at their lower ends to flow of air by natural convection which serves to cool the metal wall of heat treating section 14. A manifold 119 communicates the upper ends of each of the vertical passageways and the warm air passing therethrough into the manifold is discharged to the atmosphere through one or more stacks, not shown, but which communicate with manifold 119.

Disposed horizontally around and just below the upper edge of jacket 116 is a horizontal annular platform 118 forming the bottom of ash conveyor space 120. Platform 118 is supported from jacket 116 by means of a plurality of radial, triangular-shaped, support plates 122. Ash discharge chute 124 opens downwardly from the bottom of platform 118 at one side of the ash conveyor. The ash is moved around ash conveyor 120 to this discharge point by means of a plurality of scraper

blades 126 resting therein and which are rotated by the rotary mechanism which turns the superstructure with which the plows are associated. Thus the spent solid material or ash discharged from the top of ash cooling zone 66 is collected in a peripheral conveyor at the top of heat treating section 14 and is discharged substantially continuously from the equipment.

Extending upwardly from the outer edge of platform 118 is the ring girder side frame 128 which is a heavy cylindrical element disposed vertically with its axis substantially coincident with the vertical axis of disengaging section 12 and heat treating section 14. A ring girder 130 is disposed around the upper end of side frame 128 and serves to strengthen the upper edge of the side frame. Drive ring 132 consists of upper flange element 134, upper cylindrical section 136, horizontal or platform section 138, intermediate cylindrical section 140, lower cylindrical section 142, and conical bracing section 144. The drive ring is disposed in a generally horizontal position within ring girder 130. A plurality of horizontal thrust rollers 146 with their axes vertical are supported at uniformly spaced locations around ring girder 130. The periphery of drive ring 132 turns in contact with the primary bearings in order to maintain the associated plow equipment in a central position. A plurality of vertical thrust rollers 148 disposed with their axes horizontal are uniformly spaced around ring girder 130. These bearings tend to resist horizontal and vertical thrusts or deflections respectively of the rotating mechanism which are generated by the action of the plows turning in the upwardly moving solids bed. Horizontal rollers 146 thus ride in peripheral track 149 disposed around the outer surface of drive ring 132 just outside of intermediate cylindrical section 140. The conveyor elements 126 are attached by the means shown to the drive ring just described and rotate with it.

Disposed around the inner surface of ring girder side frame 128 and just below the ring girder 130 is an L-shaped channel 129 containing a bed 131 of fine solids such as sand. Channel 129 is of course stationary. Supported from the outer surface of lower cylindrical section 142 of the drive ring 132 is rotating seal element 133 having an inverted L-shape which extends entirely around the drive ring and also extends downwardly into seal solids bed 131. This seal prevents entry of atmospheric air into the kiln under the influence of gas blower 60 around the periphery of the drive ring and forces the air flow to enter via ash chute 124. In so flowing in through the ash chute, the air entering is countercurrently contacted by the discharging ash thereby effecting a significant degree of ash cooling and air preheating.

Disposed around the outer edge of upper flange section 134 is a T-shaped ratchet ring 150. The web of this ring is bolted to the outer edge of upper flange element 134 and provides a plurality of flat vertical ratchet surfaces on its vertical flange against which the driving mechanism hereinafter described engages to apply the tangential turning force. In this way the drive ring is rotated. These driving forces are applied hydraulically and continuously at power levels sufficient to rotate the drive ring at a velocity between about 1 and about 6 revolutions per hour.

Superimposed above upper flange element 134 are one or more spacer rings 152 and 154. The purpose of these rings is to raise or lower the plows with respect to the drive ring 132 and the upwardly moving shale bed. The spacer rings are essentially curved channel beam sections connected to one another in a circle with flanges outward so that they are readily added or removed from the side of the rotating structure.

Plow support ring 156 is in turn supported by means of a horizontal flange 158 and is connected either to the uppermost spacer ring or to the inner bolt circle on upper flange element 134 in the event that no spacer rings are employed. The plow support ring extends entirely across

the upper cross sectional area of the retort structure. It is provided with a lower deck 166, upper deck 174, and with internal bracing not shown. The three plows 160, 162, and 164 are dependent from the lower deck 166 of plow support ring 156 by means of transition sections 168, 170, and 172 respectively.

Supported on upper deck 174 of the plow support ring are disposed the plow coolant coolers 176, 178, and 180. The structure of these coolers and their operation is more clearly described in connection with Figures 2 and 3. Suffice it here to say however that these coolers are provided with suitable piping connections indicated generally as 182 by means of which the liquid coolant from the plows flows upwardly into the cooler and then is returned for circulation through the plow.

The previous description indicates generally the upflow solids-fluid contacting process and apparatus of this invention, and generally points out the relationship of the self-cooled shale plows and the rotating mechanism with the upflow shale retorting apparatus. The following description of Figures 2 through 12 is restricted to the structural detail of the plow support ring, the plows dependent therefrom, the coolant cooler superimposed thereon, and the means by which the rotating element is turned and maintained in a fixed position during the rotation.

Referring now more particularly to Figures 2 and 3, is shown the internal structure of each coolant cooler. The upper deck 174 of plow support ring 156 is shown together with hot line 190 and cold line 192 opening upwardly into and downwardly from the coolant cooler. Outer shell 194 is provided and it is supported from upper deck 174 by any form of convenient support structure not shown but indicated schematically in Figure 1. Hot line 190 opens into horizontal hot header 196 and cold line 192 opens into cold header 198 extending horizontally parallel to header 196. The hot and cold headers 196 and 198 communicate with each other through a plurality of hairpin or U-shaped finned tube sections 200, the horizontal legs of which are provided with external vertical fins to increase the heat transfer area. Disposed immediately above the bank of finned tubes is fan 202 supported and driven from shaft 204 which connects to electric motor 206. The purpose of the fan is to force cooling air downwardly within enclosure 194 in the direction of the arrows across the finned surfaces of the tubes, into bottom portion of enclosure 194, back upwardly through channels 208 and 210 to the top of enclosure 194. The reverse direction of air flow may be used if desired. Louvres 212 and 214 are manually adjusted by means of control element 216 and may direct the cooling air once through across the finned tubes, or it may discharge part of the heated air and introduce some new cooled air, or it may recirculate the air entirely within enclosure 194. One or the other of the first two cases mentioned is characteristic of operation after operating temperatures have been reached within the retort proper. The latter air flow plan is characteristic of the startup period.

As a further aid in starting up, resistance heaters 191 and 193 are provided to melt frozen coolant in hot and cold lines 190 and 192. Heater 195 is provided in the enclosure 194 to heat air therein which is circulated by fan 202 to melt the coolant in the finned U-tubes 200. An additional heater 197 is provided around reservoir 226 for the same purposes. These are not required if coolants are used which are liquid at the lowest shutdown temperatures.

The coolant circulates by natural convection through hot line 190 through the coolant cooler and back into and through the plow connected therewith through cold line 192. Since the coolant expands and contracts between the shutdown and operating extremes of temperature and because it may be chemically reactive, an inert pressuring gas is introduced into the system through

line 220 controlled by valve 22 and pressure controller 224. As the apparatus cools down following a shutdown the coolant contracts and the inert blanketing gas is introduced automatically through line 220 to maintain any desired minimal inert gas pressure in the system. A gas vessel 226 provides a reservoir for the gas under slight pressure. When the apparatus is cold and being started up, coolant as well as gas expansion occurs and the pressure may tend to rise above a certain fixed maximum value. Accordingly bleed line 228 is provided with valve 230 which is actuated by pressure controller 232. The setting of pressure controller 224 in a system using liquid sodium as the coolant and helium as the inert blanketing gas may be 0.5 p.s.i. for pressure controller 224 and 1.0 p.s.i. for pressure controller 232. If desired, these lines 220 and 228 may be connected with compressor means and gas storage means not shown so that a closed inert gas system is employed. In this way substantially no internal fluid pressures are exerted on the plow-cooler structure.

It should be understood that in the present modification three plows are shown attached to the lower deck of plow support ring 156 and a corresponding number of coolant coolers are supported on the upper deck. This particular number is not intended as a limitation in the apparatus of this invention since fewer than three as well as more than three plows and corresponding coolers may be employed depending upon the size of the retorting equipment, and particularly its upper diameter.

Referring now more particularly to Figure 4, a partial plan view of the apparatus of Figure 1 is shown in somewhat greater detail. Ring girder side frame 128 appears together with the ring girder 130 at the upper end thereof. Disposed at uniform intervals around the periphery of ring girder 130 are alternate horizontal thrust rollers 146 and vertical thrust rollers 148 by means of which the rotation of the plow drive ring is guided.

The horizontal platform surface 138 of plow drive ring 132 is shown having a small clearance 240 between its outer edge and the inner surface of ring girder 130. Upper flange element 134 of the drive ring is provided with an inner and outer bolt circle. Ratchet ring 150 is shown bolted to the outer bolt circle and its configuration is clearly shown in this figure. To the inner bolt circle is bolted plow support ring 156.

Disposed around the inner surface of ring girder 130 are stationary cleats 242 by means of which each hydraulic drive cylinder 244 is pivotably anchored in a stationary position. Ratchet ring engaging heads 246 are connected at the end of each of the piston rods of the hydraulic drive cylinders 244. Shoe guides 248 ride around and overlap the upper and lower exposed edges of ratchet ring 150 and maintain engaging head 246 in a substantially fixed radial position with respect to ratchet ring 150. Engaging head 246 is spring loaded by means of spring 250 so that it is biased radially inward at its extreme end into continuous contact with the outer surface of the ratchet ring. Thus as each hydraulic drive cylinder 244 is extended, shoes 248 prevent radial outward movement of engaging head 246 and the engaging head engages the ratchet ring so that the drive cylinders can apply a tangential rotating force effectively to the periphery of the drive ring.

Although Figure 4 is a fragmentary view of approximately one-half of the ring girder, of the drive ring, and of the ratchet ring, and showing the entire upper surface of the plow support ring, it is apparent that six drive cylinders 244 are provided spaced 60° apart around the annular space between the ratchet ring 150 and the inner surface of the ring girder 130. To obtain continuous rotation of the rotary equipment, it is most desirable that at any given time in the cycle a first pair of these six hydraulic drive cylinders is being retracted and then pre-engaged with the ratchet ring by the application of low hydraulic oil pressure while the second and third

pair are at two different stages of completion of their power strokes. At the time that the first pair just begins the retraction and pre-engagement strokes, the second pair is just beginning the power stroke while in the third pair the power stroke is approximately 50% complete. The third pair of course will complete the power stroke before the second pair. As soon as this completion occurs, the first pair of cylinders, which has now been retracted and pre-engaged under low pressuring, is thrown immediately into the beginning of the power stroke while the retraction and pre-engagement continues with the third pair which has just completed its power stroke. This sequence of operations continues in a cycle to maintain steady rotation at very high torque and very low velocities of from about 1 to about 6 revolutions per hour.

Also shown in Figure 4 is the structure of plow support ring 156. The upper and lower decks are segmented and consist of flat plates 252 welded at right angles to vertical stiffening plates 254 which project from above the upper deck to below the lower deck forming flanges. These plates 254 are drilled horizontally in the flange portions so that all the sections may be bolted securely together. The underside of this structure including the flanges is shown in the attached Figure 5 subsequently described.

The azimuthal and radial distribution of the three plows on plow support ring 156 is also shown in Figure 4. For example the outermost plow 256 is provided with shoe 258 and transition section 260 by means of which it is connected to the lower deck of plow support ring 156. Openings 262 and 264 are provided in the upper deck of the plow support ring through which extend hot line 190 and cold line 192 respectively for conducting the coolant flow between the plow and the coolant coolers.

In the present modification three such plows are employed. They are disposed radially with respect to the center of rotation 266 of the plow support ring and azimuthally with respect to one another so that net resultant horizontal force on the plow support ring is as nearly zero as possible thereby minimizing the load on the horizontal and vertical thrust rollers mounted in the ring girder and thereby also equalizing the loads on each of the four hydraulic drive cylinders which are in the power stroke at any given time.

The radial dimension of the leading edge of each plow shoe 258 decreases successively with plows disposed radially farther from the center of rotation. In other words the innermost plow has the widest shoe and the plows disposed farther out have successively narrower shoes. Furthermore, the radial disposition of the plows from the center of rotation 266 is adjusted with respect to the relative shoe widths so that the entire cross section of the rising mass of shale is swept and agitated by the leading edge of a plow shoe once for every rotation of the plow support ring, with the exception of a very small section at the center of rotation and a very thin section adjacent the outer edge of the rising mass of shale. This is shown schematically only in Figure 4.

Referring now more particularly to Figure 5, a perspective view of the plows as viewed from beneath plow support ring 156 is shown. The structure of all plows is generally the same, each has the same number of corresponding elements as the other two, and only the physical dimensions vary somewhat from plow to plow.

The individual flanged sections of lower deck 166 clearly appear together with the drilled holes required in the flanges for bolting the various sections together. The three plows shown are located along different radii from the center of rotation, plow 162 being closest to the center, plow 160 being located at an intermediate radius, and plow 164 being located nearest the periphery of plow support ring 156.

In general the helical curvature of the leading and

trailing edges or struts of plows 160, 162, and 164 is apparent in this figure, the cylindrical curvature of the plows being particularly apparent with respect to plow 162. Each of these plows is provided at its lower extremity with a plow shoe 270, 272, and 274, respectively, and each plow is connected to the lower deck 166 of plow support ring 156 by means of transition sections 168, 170, and 172.

Referring now to transition section 172 as representative of the others as well, the transition section is fabricated from leading conical section 276 and trailing conical section 278, both of relatively small radii and disposed with their apices downward, spaced apart from one another along an arc around the center of rotation. The transition section is then completed by interconnecting the open edges of the leading and trailing conical sections referred to by means of inner conical side section 280 and an outer conical side section not shown but corresponding to outer conical side section 282 in transition section 168. These conical side sections have large radii relative to the radii of the leading and trailing conical sections. The curvature of these conical side sections is such that the cone from which the inner conical section 280 is taken has its apex upward while the cone from which the outer conical section corresponding to 282 was taken has its apex downward. The slope of the sides of all of the four conical sections in each transition section is the same.

The structure of the transition section thus formed comprises a closed exterior surface, welded at its upper edge to lower deck 166 of plow support ring 156, which curves along an arc around the center of rotation of the plow support ring, and which tapers downwardly. Each of the three transition sections 168, 170, 172 is constructed in general from four such conical sections. The radii of the conical side sections are selected so that the inner and outer sections join with the conical leading and trailing conical sections tangentially, such as at welds 284 and 286 in transition section 172.

The transition sections are each extended downwardly a short distance below a horizontal adapter plate 288 shown more clearly in Figure 6. This extension exists all the way around the periphery of the adapter plate, except adjacent the trailing conical section 278. At this point it is provided with a helicoid surface 290, the helical slope of which is substantially identical to that of the trailing strut of the plow 164. The purpose of this cut-away portion is to prevent exposure of any flat horizontal surfaces against the rising bed of solids. Such sloping surfaces are provided so as to have a slope which exceeds the "get-away" angle. This angle is expressed in degrees from a horizontal reference and is defined as the angle necessary to keep any submerged surface from restricting the upward movement of solids at a time when the solids feed rate is at a maximum and the plow rotation rate is at a minimum. For the retorting of shale in the apparatus of the invention as described in connection with Figure 1, this angle was approximately 15°. Helicoid surface 290 had a slope of about 33°.

Referring now more particularly to plow 160 as representative of the other plows also, this member is composed of a leading strut 292 and a trailing strut 294, each of which is bent into a helical curve of different angles so as to converge toward one another. The struts are hollow tubular members of circular cross section. At the point of convergence of these struts plow shoe 270 is securely attached. The tube radii of the leading and trailing helical struts 292 and 294 are relatively low. The exterior surface of plow 160 is completed by an inner cylindrical side section, not shown but corresponding to section 296 on plow 164, and an outer cylindrical side section 298, each of relatively large radii. These inner and outer cylindrical side sections are concentric with each other and are welded at their edges to the

11

leading and trailing helical struts 292 and 294 at the locus of innermost and outermost tangent points, respectively, of each strut.

The detail of the inner structures of the transition sections, the plows, and the plow shoes are illustrated in Figures 6 through 12 hereinafter more fully described. These drawings are all sectional views of the complete plow element, and these sections are taken in the directions indicated in Figure 5 by the section lines shown on plow 162, as well as in Figure 6.

Referring now more particularly to Figure 6, a developed vertical cross section view through plow 162 is shown. This is a view of the plow support ring 156 with its upper and lower decks 174 and 166 respectively, and showing transition section 170, plow 162, and shoe 272 as they would appear as if plow 162 and its transition section 170 were cut in the manner indicated in Figure 5 and viewed at right angles from the axis of rotation. Leading conical section 276 and trailing conical section 278 of transition section 170 are shown. Extending upwardly from adaptor plate 288 are hot line 190 and cold line 192 by means of which the plow coolant is circulated through the coolant coolers previously described. Vertical stiffening plates 300 disposed radially within transition section 170 between the conical side sections previously described are employed to strengthen the structure.

Extending downwardly and to the right at a helix angle of about 45° is leading helical strut 292. Leading downwardly and to the right at an angle of about 33° is trailing helical strut 294, the adjacent parts of the leading and trailing struts converging at point 302. As indicated previously, each of these leading and trailing struts is hollow and cylindrical in cross section and thus form a flow path for the plow coolant downwardly from cool line 192 into plow shoe 272, and from the plow shoe upwardly toward hot line 190 and the coolant coolers in the direction of the arrows.

The outer envelope of the plow element is completed by means of the inner and outer cylindrical side sections 296 and 298 not shown in Figure 6, but previously described in connection with Figure 5. This forms a hollow structure which is closed at its lower end by means of shoe sole plate 304 and plow shoe 272. The plow and shoe are welded or otherwise attached securely together forming a fluid tight envelope supported from adaptor plate 288. In general this structural element comprises a helical hollow cantilever beam.

Since the thermal and mechanical stresses to which this beam is subjected during plowing of the burning shale are quite severe, further internal strengthening of this outer cantilever beam is frequently desirable. This is accomplished by providing a second or inner cantilever beam supported also from adaptor plate 288 and which extends downwardly at an angle in a curving path in the space provided between the inner and outer cylindrical side sections referred to previously and also between the leading and trailing struts of the plow. This inner cantilever beam comprises a plurality of converging helicoids 306, 308, and 310, the upper ends of which are spaced apart from one another along the same radius as the leading and trailing struts 292 and 294 on the lower surface of the adaptor plate 288. These particular helicoids are helical surfaces generated by radii extended at right angles from the longitudinal axis of a cylinder through a helix scribed on the surface of that cylinder. These helicoids converge toward an intersection 312 near the intersection 302 of the adjacent surfaces of leading and trailing struts 292 and 294 of the outer cantilever beam. The inner and outer edges of the three helicoids are connected respectively together by an inner and an outer cylindrical side section forming the inner cantilever beam having a curved III-shaped cross section when three helicoids are employed. This is more clearly shown in Figure 10 subsequently described.

12

The completed plow element thus comprises an outer cantilever beam comprising a pair of converging helical struts and the associated cylindrical side sections surrounding an inner cantilever beam comprising converging helicoids and their associated cylindrical side sections, both the outer and inner cantilevers being anchored at adaptor plate 288 in the manner shown generally in Figure 6. The adjacent outer cylindrical side sections and the adjacent inner cylindrical side sections form double outer and inner metal walls of the plow structure.

Disposed at spaced intervals along the rear of trailing strut 294 are parallel void sealing plates 339. These are nearly horizontal plates having the transverse shape shown in Figure 10 and are provided to prevent gas flow down through an elongated helical void which may exist behind the trailing strut.

Referring now more particularly to Figure 7, which is a plan view of the plow shoe, the intersection of leading helical strut 292 with plow shoe 272 is shown. The leading edge of the shoe is protected by a wear plate 320. The shoe consists of generally triangular-shaped lower or sole and upper surfaces 304 and 322 respectively. The coolant flow is in the direction indicated by the arrows in Figure 6, namely downwardly through trailing helical strut 294 toward the plow shoe 272. A first portion of the coolant bypasses directly through primary bypass opening 324 where the helical struts 292 and 294 have converged, then directly into the leading helical strut 292, and then upwardly toward the coolers. The remaining portion flows through entrance 326 into plow shoe 272. Here the flow splits with a first portion leaving the shoe through secondary bypass opening 328 and flows directly into leading strut 292. The portion of coolant remaining in the plow shoe 272 is directed laterally toward the inner tip of the shoe by means of primary baffle 330, extending angularly from the outer portion of the shoe toward the inner portion. This flow again splits and a first portion flows through opening 332 between primary baffle 330 and secondary baffle 334. The remaining portion is directed around the end of secondary baffle 334 and progresses back outwardly along the leading edge of the shoe into admixture with first portion flowing through opening 332. This combined flow then passes back toward the outer edge of shoe 272 along the leading edge thereof and flows through outlet 336 into leading strut 292.

The entire coolant flow is reformed then at the lower extremity of leading strut 292 and progresses upwardly in the direction indicated by the arrows in Figure 6. Part way from the shoe 272 to the adaptor plate 288, part of the coolant stream enters the inner cantilever beam structure through openings 321 in the leading strut and openings 323 and 325 in the helicoids. It then flows parallel to the remaining flow in leading strut 292 through the inner or helicoid cantilever and re-enters the leading strut 292 via openings 327 and 329 in the helicoids and opening 331 in the strut. The entire coolant stream is again reformed just below adaptor plate 288 as the coolant flows upwardly through hot line 190. Additional openings 333, 335, and 337 are provided in the rear helicoid and in the helicoid side sections to maintain the space between the double walls of the plows filled with coolant.

Referring now more particularly to Figure 8, a plan view in cross section of the transition section 170 shown in Figure 6 is illustrated. The four conical sections which make up the transition section are clearly shown in this drawing. The leading and trailing conical sections 276 and 278, with their apices downward, are shown joined tangentially to the inner and outer conical side sections 280 and 282 with their apices upward and downward respectively. Adaptor plate 288 appears at the bottom of transition section and the coolant riser lines 190 and 192 are shown. The radial stiffening plates 300 are connected across between the inner and outer cylindrical side sections.

Referring now more particularly to Figure 9, an end

elevation view of the transition section across section is shown. Riser line 192 extending upwardly from adaptor plate 288 is shown. The sloping inner and outer conical side sections 280 and 282 are shown attached to lower deck 166 of the plow support ring. The upper edges of inner and outer cylindrical side sections 296 and 298 of the outer cantilever beam are shown attached to trailing helical strut 296. A portion of the inner or helicoid cantilever beam is shown including outer and inner cylindrical side sections 314 and 316. The upper end of the trailing helicoid 306 is also shown. The tapering nature of the transition section and the manner in which it is connected by means of the adaptor plate to the inner and outer cantilever beams are clearly apparent.

Referring briefly to Figure 10, trailing cylindrical helical strut 294, with one of the attached void sealing plates 339, and leading strut 292 together with outer and inner cylindrical side sections 298 and 296 making up the outer cantilever beam are shown. The trailing, intermediate, and leading helicoids 306, 308, and 310 respectively, together with the outer and inner cylindrical helicoid side sections 314 and 316 respectively, make up the inner cantilever beam. These two cantilever beams are anchored to adaptor plate 288 as shown in Figure 6. The inner cantilever reinforces and stiffens the outer cantilever by direct mechanical contact in the region of helicoid intersection 312 also as shown in Figure 6.

The pairs of immediately adjacent inner cylindrical side sections and outer cylindrical side sections of the inner and outer cantilevers respectively comprise the double inner and outer walls of the plow which provide the strength necessary to agitate the solids during combustion and through which heat is transferred from the burning solids to the coolant. It is absolutely essential that the thin space between these two double walls be filled with coolant to present a very low thermal resistance to heat flow into the principal coolant flow which passes upwardly between the helicoids. Therefore apertures 341 and 343 are provided in the outer cylindrical section 316 and apertures 345 and 347 are provided on the inner cylindrical section 314 of the inner cantilever in order to insure the presence of an analogous liquid coolant film between the inner and outer cylindrical side sections respectively of the inner and outer cantilever beams. Openings 341 and 343 are also shown in Figure 6. It is not believed that any substantial flow of coolant occurs between the double walls, but the presence of the coolant markedly facilitates heat transfer therethrough into the principal coolant flow within the inner cantilever.

Referring now more particularly to Figure 11, this is a cross section view of the composite plow structure taken substantially at the point at which the inner cantilever beam converges with the outer beam. It is analogous to the section shown in Figure 10. The leading and trailing helical struts 292 and 294 together with the inner and outer cylindrical side plates 296 and 298 are shown. The inner or helicoid cantilever again appears showing the addition at different points of curved bearing plates 340 and 342 by means of which the end of the inner cantilever beam is loaded by deflections of the outer cantilever beam.

Reference has previously been made, with respect to the double walls comprising the outer cylindrical side plates and the inner cylindrical side plates of the concentric cantilever beams, to the importance of the thin film of coolant within these double walls. The same considerations are important with respect to the wear plate 320 which is disposed around the leading edge of plow shoe 272.

In Figure 12 is an enlarged cross section elevation view of the plow shoe 272 shown in Figures 5, 6, and 7. The lower end of leading strut 292 is shown converging with upper surface 322 of plow shoe 272. The upper surface curves around the toe 344 and becomes sole plate 304. Wear plate 320 is wrapped around the outside

75 to receive a mass of solids from said hopper and force

of toe 344 of shoe 272 and spaced uniformly therefrom by means of spacers 346. The wear plate is welded across the top surface 322 and across sole plate 304 and along the nearly vertical sides of the shoe as indicated by weld 348. This forms between toe 344 and wear plate 320 a thin semi-cylindrical space 350 into which is introduced a volume of coolant liquid sufficient to fill the space through opening 352 in the end of the toe. This provides for ready heat transfer through the wear plate and the toe into the leading edge of the shoe through which the coolant is circulated. Opening 352 is permanently closed after the wear plate volume 350 is filled.

The apparatus of the present invention was applied in the retorting of Colorado oil shale analyzing between about 28 and 40 gallons per ton. The feed rate was 350 tons per day. The solids feeder cylinder contained within the feeder case was 5.5 feet in diameter and had a stroke of 2.0 feet. The height of the apparatus to the top of the ring girder was about 46 feet. The outside diameter of the entire structure at this point was about 30 feet, this being the outside diameter of the ring girder side frame shown in Figure 1. The plow support ring was 16 feet in diameter and 2.0 feet in thickness and supported three plows substantially as indicated in Figure 5. The inner and outer cylindrical side sections of the inner and outer cantilever elements of the plows were fabricated from stainless steel plate about 0.5 inch in thickness. The leading strut of each plow was a helix formed from a nominal 8-inch schedule-80 stainless steel pipe bent into a 45° helix. The trailing strut was an identical pipe formed into a helix of approximately 33°. The weight of each plow and its transition section was approximately 6000 pounds.

The coolers superimposed above the plow support ring were contained in enclosures approximating 15 feet in height by 9 feet in width by 7 feet in depth. Each cooler contained 9 hairpin loops of 4-inch nominal mild steel pipe provided with transverse radial aluminum fins spaced 0.25 inch apart from each other and having an outside diameter of 6.0 inches. The finned length of each loop was 5.5 feet. A fan driven by a 7.5 horsepower motor was disposed over each bank of finned tubes.

The coolant selected for this system was metallic sodium and the inventory in each cooler plow combination was approximately 2000 pounds. The circulation of molten sodium within the plows was by natural convection and at a rate of about 9000 pounds per minute. During normal operations the temperature of sodium into the coolers was about 425° F. and that out of the coolers was about 375° F.

Other coolants may be substituted, such as the sodium-potassium (NaK) eutectic, lithium, potassium, molten salts such as the alkali metal nitrates and nitrites, lead, and the like. For operation under pressure, water may be circulated or boiled in the plows. The enumerated materials are intended as representative non-exclusive, suitable heat transfer agents.

A particular embodiment of the present invention has been hereinabove described in considerable detail by way of illustration. It should be understood that various other modifications and adaptations thereof may be made by those skilled in this particular art without departing from the spirit and scope of this invention as set forth in the appended claims.

We claim:

1. In an apparatus for the contacting of fluids and solids which comprises a contacting vessel, a foraminous fluid disengaging vessel, and a solids feeder case disposed at successively lower levels in a column, an inclined solids inlet hopper opening downwardly into the side of said feeder case, an oscillating vertically-acting piston solids feeder disposed in said feeder case, means for oscillating and reciprocating said piston feeder so as to receive a mass of solids from said hopper and force

it upwardly into and successively through said disengaging and contacting sections, a closed separator vessel surrounding said disengaging vessel, and means for removing fluids therefrom to maintain flow of fluid downwardly through the rising mass of solids, the improvement in combination therewith of means for agitating the solids within said contacting section which comprises a plow support ring, means supporting said support ring in a rotatable position above the upper end of said contacting section, means for rotating said support ring in this position, a plurality of plows secured to the lower surface of said support ring and extending downwardly into the rising mass of solids in said contacting section; each of said plows comprising a leading and a trailing hollow tubular strut connected at their upper ends at points spaced apart from each other along an arc around the center of rotation of said support ring and extending downwardly therefrom at different helical angles into convergence with each other below the upper end of said contacting section, an outer cylindrical side section secured tangentially at its leading and trailing edges respectively to said leading and trailing struts substantially at the loci of the outermost tangent points thereof, an inner cylindrical side section concentric with said outer side section and secured tangentially at its leading and trailing edges respectively to said leading and trailing struts substantially at the loci of innermost tangent points thereof, a plow shoe having an extended width in a radial direction relative to the axis of rotation and secured to said helical struts adjacent the convergence thereof; a plurality of heat exchange means supported upon said plow support ring, means connecting said leading and trailing tubular struts of one of said plows to one of said heat exchange means forming therewith a closed fluid flow circuit, a body of coolant filling a substantial part of said closed circuit, and means for contacting the exterior surface of each of said heat exchange means with a heat exchange medium.

2. An apparatus according to claim 1 wherein said means supporting said plow support ring comprises an annular-shaped platform surrounding and connected to said contacting section adjacent the upper end thereof, a cylindrical ring girder side frame extending upwardly from the outer edge of said platform, a ring girder extending around the upper periphery of said side frame, a plurality of horizontal and vertical thrust rollers disposed in and uniformly spaced around the inner surface of said ring girder, a drive ring supported and guided by direct contact with said vertical thrust rollers disposed within said ring girder so as to be rotatable therein, said drive ring being provided with a radial flange at its upper end, said plow support ring being secured by means of said radial flange to said drive ring and rotatable therewith.

3. An apparatus according to claim 2 in combination with a ratchet ring of T-shaped cross section attached to and extending radially outward from the flange at the top of said drive ring and providing on its outer surface a ratchet comprising a plurality of flat vertical surfaces against which tangential forces are applied, a plurality of hydraulic cylinders disposed around the periphery of said drive ring, each of said cylinders being pivotably secured to the inner surface of said ring girder, a spring loaded ratchet ring engaging head connected at the end of the piston rod extending from each of said hydraulic cylinders and slidably coupled to said ratchet ring, whereby hydraulic fluid under pressure supplied to said cylinders effects drive ring and plow support ring rotation.

4. An apparatus according to claim 2 in combination with an ash chute conduit opening downwardly from the annular-shaped platform extending around the top of said contacting section, a plurality of solids scraper elements extending downwardly from said drive ring into the annular space above said platform and between said ring girder side frame and the upper part of said contacting section, said scraper elements being spaced apart

from one another and rotating with said drive ring to convey spent solids discharged at the top of said contacting section around said annular space toward the upper entrance to said ash chute conduit.

5. An apparatus according to claim 4 in combination with a seal channel disposed around the inner surface of the ring girder side frame, a body of granular solid material filling said channel to a substantial depth, a seal element of L-shaped cross section attached to and extending outwardly and downwardly from the periphery of the drive ring into said body of solid material to inhibit fluid flow between said drive ring and said ring girder side frame whereby fluid drawn downwardly through the contacting section is forced to enter said contacting section via said ash chute conduit in direct countercurrent heat exchange relationship to the solids discharging therethrough.

6. An apparatus according to claim 2 in combination with at least one continuous spacer ring disposed between the upper flange element of said drive ring and a peripheral flange disposed around said plow support ring, the presence of which determines the depth to which said plows extend downwardly into the contacting section.

7. An apparatus according to claim 1 wherein each of said plurality of heat exchange means disposed upon said plow support ring comprises a closed shell, shell support means connected to the upper deck of said plow support ring, a hot header conduit and a cold header conduit disposed adjacent the wall of said shell, a plurality of externally finned U-shaped heat exchange tubes connected in parallel between said header conduits, means for circulating a fluid within said enclosure across said finned tubes, and means for controlling the removal and addition of fluid from and to said shell, whereby coolant flowing from said plow into and through said heat exchange means and back to said plow is subjected to temperature control.

8. An apparatus according to claim 7 wherein the coolant circulated through the circuit comprising said plow and heat exchanger means comprises a liquid reactive in the atmosphere, in combination with an inlet and pressure control means therefor opening into the coolant circuit for an inert gas and adapted to maintain a pressure therein above a fixed minimum pressure, and an outlet and pressure control means therefor opening from said circuit to maintain pressures therein below a fixed maximum.

9. An apparatus according to claim 7 in combination with heating means disposed within said shell, and heating means disposed adjacent the conduits connecting the heat exchange means to the associated plow, said heating means being adapted to heat the fluid circulated therein to warm the coolant during apparatus start-up.

10. An apparatus according to claim 1 in combination with an inner reinforcing cantilever beam element contained within said plow structure and comprising a plurality of helicoids with their upper ends spaced apart from one another along substantially the same arc as said struts and extending downwardly along different helical angles into convergence just above the convergence of said leading and trailing struts, a second outer cylindrical side section disposed within said plow and adjacent said first-named outer side section thereof and secured to the outer edges of said helicoids, a second inner cylindrical side section disposed within said plow and adjacent said first named inner side section thereof and secured to the inner edges of said helicoids forming the inner reinforcing cantilever; and curved bearing plates disposed adjacent the convergence of said helicoids and in contact with the leading and trailing sides of the trailing and leading tubular struts respectively to load mechanically the lower end of said inner reinforcing cantilever with said plow at this point; said second inner and outer cylindrical side sections and said helicoids being provided along their extended surfaces with apertures to

insure the presence of coolant between the double walls formed by the adjacent pairs of inner and outer side sections and between said helicoids, the trailing side of said leading helical strut being provided with a coolant outlet into and a coolant entrance from the space between the converging helical struts occupied by said inner reinforcing cantilever, said outlet and entrance being located respectively near the bottom and the top of said leading helical strut.

11. An apparatus according to claim 1 in combination with a plow transition section connecting each of said plows to the lower deck of said plow support ring and which comprises an adapter plate disposed below and substantially parallel to the lower deck of said plow support ring, the plate having a shape which is geometrically similar to the horizontal cross section of said plow at its upper end, the upper ends of said leading and trailing struts and of said inner and outer cylindrical side sections being attached to the lower side of said adapter plate, a leading and a trailing conical section tapering downward attached at their upper ends to said lower deck and adjacent their lower ends to the respective ends of said adapter plate, an inner and an outer conical side section tapering upward and downward respectively attached at their upper ends to said lower deck and adjacent their lower ends to the respective sides of said adapter plate and connecting tangentially with said leading and trailing conical sections and a plurality of strengthening plates disposed within each of said transition sections in vertical planes radially with respect to the axis of rotation of said support ring; and wherein said means connecting said leading and trailing struts to one of said heat exchange means comprises a cold conduit opening upwardly from an opening in said adapter plate at the upper end of said trailing strut and a hot conduit opening upwardly from another opening in said adapter plate at the upper end of said leading strut, both of which conduits extend through the lower and upper decks of said plow support ring into connection with one of the superjacent heat exchange means.

12. An apparatus according to claim 1 wherein said plow shoe comprises a closed hollow member elongated from the outer surface of the plow radially inward toward the axis of rotation, the lower surface of said shoe extending back from the leading radial edge thereof into connection with the lower end of said trailing strut and the upper surface of said shoe extending back and upwardly into the leading strut and then downward into contact with said lower surface at a point below the convergence of the adjacent sides of the leading and trailing struts, said plow shoe provided with coolant flow openings to permit coolant entrance into said shoe from said trailing strut and coolant discharge into said leading strut, an internal baffle within said shoe to direct part of said flow radially inward and then radially outward inside the leading edge thereof, a wear plate folded over the external surface of said leading edge and spaced apart therefrom by a fluid tight space and secured at its edges to said shoe, and a volume of high thermal conductivity fusible material substantially filling said space.

13. A heavy-duty apparatus for the agitation of a dense compact mass of large size solids which comprises a vessel enclosing said mass of solids, a plow support ring, means supporting said support ring in a rotatable position above the upper end of said mass of solids, means for rotating said support ring in this position, a plurality of plows secured to the lower surface of said support ring and extending downwardly into the solids mass; each of said plows comprising a leading and a trailing hollow tubular strut connected at their upper ends at points spaced apart from each other along an arc around the center of rotation of said support ring and extending downwardly therefrom at different helical angles into convergence with each other below the upper end of said solids

70
75

mass, an outer cylindrical side section secured tangentially at its leading and trailing edges respectively to said leading and trailing struts substantially at the loci of the outermost tangent points thereof, an inner cylindrical side section concentric with said outer side section and secured tangentially at its leading and trailing edges respectively to said leading and trailing struts substantially at the loci of innermost tangent points thereof, a plow shoe having an extended width in a radial direction relative to the axis of rotation and secured to said helical struts adjacent the convergence thereof.

14. An apparatus according to claim 13 in combination with an inner reinforcing cantilever beam element contained within said plow structure and comprising a plurality of helicoids with their upper ends spaced apart from one another along substantially the same arc as said struts and extending downwardly along different helical angles into convergence just above the convergence of said leading and trailing struts, a second outer cylindrical side section disposed within said plow and adjacent said first-named outer side section thereof and secured to the outer edges of said helicoids, a second inner cylindrical side section disposed within said plow and adjacent said first-named inner side section thereof and secured to the inner edges of said helicoids forming the inner reinforcing cantilever; and curved bearing plates disposed adjacent the convergence of said helicoids and in contact with the leading and trailing sides of the trailing and leading tubular struts respectively to load mechanically the lower end of said inner reinforcing cantilever with said plow at this point.

15. An apparatus according to claim 13 in combination with a plow transition section connecting each of said plows to the lower deck of said plow support ring and which comprises an adapter plate disposed below and substantially parallel to the lower deck of said plow support ring, the plate having a shape which is geometrically similar to the horizontal cross section of said plow at its upper end, the upper ends of said leading and trailing struts and of said inner and outer cylindrical side sections being attached to the lower side of said adapter plate, a leading and a trailing conical section tapering downward attached at their upper ends to said lower deck and adjacent their lower ends to the respective ends of said adapter plate, an inner and an outer conical side section tapering upward and downward respectively attached at their upper ends to said lower deck and adjacent their lower ends to the respective sides of said adapter plate and connecting tangentially with said leading and trailing conical sections, and a plurality of strengthening plates disposed within each of said transition sections in vertical planes radially with respect to the axis of rotation of said support ring.

16. An apparatus according to claim 1 wherein said solids exist at an elevated temperature in combination with self-cooling means for each of said plows which comprises a plurality of heat exchanger enclosures supported on top of said plow support ring, a hot header conduit and a cold header conduit disposed adjacent the wall of said enclosure, a plurality of externally finned U-shaped heat exchange tubes connected in parallel between said header conduits, means for circulating a fluid within said enclosure across said finned tubes, means for controlling the removal and addition of fluid from and to said enclosure, a hot conduit opening upwardly from the top of said leading strut into said hot header, a cold conduit opening downwardly from said hot header into the top of said trailing strut, a body of coolant filling a substantial portion of the circuit including said struts, conduits, headers, and heat exchange tubes, whereby coolant flowing from said plow into and through said heat exchange means and back to said plow is subjected to temperature control.

17. An apparatus according to claim 13 wherein said

means for supporting said support ring comprises a cylindrical ring girder side frame extending upwardly around the mass of said solids, a ring girder extending around the upper periphery of said side frame, a plurality of horizontal and vertical thrust rollers disposed in and uniformly spaced around the inner surface of said ring girder, a drive ring supported and guided by direct contact with said vertical thrust rollers disposed within said ring girder so as to be rotatable therein, said drive ring being provided with a radial flange at its upper end, said plow support ring being secured by means of said radial flange to said drive ring and rotatable therewith, and wherein said means for rotating said support ring comprises a ratchet ring of T-shaped cross section attached to and extending radially outward from the flange at the top of said drive ring and providing on its outer surface a ratchet comprising a plurality of flat vertical surfaces against which tangential forces are applied, a plurality of hydraulic cylinders disposed around the periphery of said drive ring, each of said cylinders being pivotably secured to the inner surface of said ring girder, a spring-loaded ratchet ring engaging head connected at the end of the piston rod extending from each of said hydraulic cylinders and slidably coupled to said ratchet ring, whereby hydraulic fluid under pressure supplied to said cylinders effects drive ring and plow support ring rotation.

18. An apparatus according to claim 17 in combination with at least one continuous spacer ring disposed between the upper flange element of said drive ring and a peripheral flange disposed around said plow support ring, the presence of which determines the depth to which said plows extend downwardly into said dense mass of solids.

19. An apparatus according to claim 13 wherein said plow shoe comprises a closed hollow member elongated from the outer surface of the plow radially inward toward the axis of rotation, the lower surface of said shoe extending back from the leading radial edge thereof into connection with the lower end of said trailing strut and the upper surface of said shoe extending back and upwardly into the leading strut and then downward into contact with said lower surface at a point below the convergence of the adjacent sides of the leading and trailing struts, said plow shoe provided with coolant flow openings to permit coolant entrance into said shoe from said trailing strut and coolant discharge into said leading strut, an internal baffle within said shoe to direct part of said flow radially inward and then radially outward inside the leading edge thereof, a wear plate folded over the external surface of said leading edge and spaced apart therefrom by a fluid tight space and secured at its

edges to said shoe, and a volume of high thermal conductivity fusible material substantially filling said space.

20. An apparatus according to claim 13 in combination with a plurality of parallel substantially horizontal void sealing plates spaced apart from each other and secured to the rearward surface of said trailing strut, said plates being provided to inhibit flow of fluid through the solids mass immediately behind said trailing strut.

21. An apparatus according to claim 13 in combination with means for receiving said solids at a lower level within said vessel and forcing said solids upwardly into and through said vessel, thereby discharging said solids at the top thereof of said vessel.

22. An apparatus according to claim 21 wherein said solids exist at an elevated temperature in combination with self-cooling means for each of said plows which comprises a plurality of heat exchanger enclosures supported on top of said plow support ring, a hot header conduit and a cold header conduit disposed adjacent the wall of said enclosure, a plurality of externally finned U-shaped heat exchange tubes connected in parallel between said header conduits, means for circulating a fluid within said enclosure across said finned tubes, means for controlling the removal and addition of fluid from and to said enclosure, a hot conduit opening upwardly from the top of said leading strut into said hot header, a cold conduit opening downwardly from said cold header into the top of said trailing strut, a body of coolant filling a substantial portion of the circuit including said struts, conduits, headers, and heat exchange tubes, whereby coolant flowing from said plow into and through said heat exchange means and back to said plow is subjected to temperature control.

23. A heavy-duty apparatus according to claim 13 in which the vessel communicates at its lower end with the upper end of a foraminous fluid disengaging vessel, the lower end of the disengaging vessel communicates with means for forcing said solids upwardly through said disengaging vessel and said vessel enclosing said mass of solids, a closed separator vessel surrounds said disengaging vessel, and means are provided for removing fluids therefrom to maintain flow of fluid downwardly through the rising mass of solids.
